United States Patent Office

Des. 194,998
Patented Apr. 9, 1963

194,998

JUG

Alvin A. Miller, Sunnyside, Wash., assignor to Wescos Plastics, Inc., Sunnyside, Wash., a corporation of Washington

Filed Sept. 1, 1961, Ser. No. 66,592

Term of patent 14 years

(Cl. D58—5)

FIG. 1 is a perspective view of a jug embodying my new design.

FIG. 2 is a side elevation view thereof.

FIG. 3 is a cross section taken on line 3—3 in FIG. 2.

FIG. 4 is a vertical section taken on line 4—4 in FIG. 3.

The side not shown is a mirror image of the side shown in FIG. 2.

I claim:

The ornamental design of a jug, substantially as shown and described.
